US0D1112960S

(12) **United States Design Patent** (10) **Patent No.:** **US D1,112,960 S**
(45) **Date of Patent:** **** Feb. 10, 2026**

(54) **PROTECTIVE SCREEN FOR A WEED WHIPPER SHIELD**

(71) Applicant: **Vista Studios, Inc.**, White Bear Lake, MN (US)

(72) Inventor: **Joseph Stafford**, White Bear Lake, MN (US)

(73) Assignee: **Vista Studios, Inc.**, White Bear Lake, MN (US)

(**) Term: **15 Years**

(21) Appl. No.: **29/935,101**

(22) Filed: **Mar. 29, 2024**

(51) LOC (15) Cl. **08-03**

(52) U.S. Cl.

USPC **D8/8**

(58) **Field of Classification Search**

CLAIM

The ornamental design for a protective screen for a weed whipper shield, as shown and described.

DESCRIPTION

FIG. 1 is a top perspective view of the protective screen for a weed whipper shield;

FIG. 2 is a front elevational view of the protective screen for a weed whipper shield;

FIG. 3 is a rear elevational view of the protective screen for a weed whipper shield;

FIG. 4 is a left side view of the protective screen for a weed whipper shield;

FIG. 5 is a right side view of the protective screen for a weed whipper shield;

FIG. 6 is a top plan view of the protective screen for a weed whipper shield; and,

FIG. 7 is a bottom plan view of the protective screen for a weed whipper shield.

1 Claim, 5 Drawing Sheets
